UNITED STATES PATENT OFFICE.

LLOYD G. COPEMAN, OF FLINT, MICHIGAN.

REFRIGERATING SYSTEM AND METHOD OF OPERATING THE SAME.

Application filed September 18, 1926. Serial No 136,245.

This invention relates to a refrigerating system and method of operating the same and has to do particularly with the provision of a refrigerating unit adapted to be automatically and continuously operated and provided with an auxiliary refrigerating medium, and a second refrigerating unit adapted to be operated by said auxiliary medium.

It is the object of this invention to provide a cooling unit for the refrigerating chamber of a refrigerating cabinet, the refrigerating coils, or refrigerating passageways of which are embedded in cast stone, such cast stone forming the walls of the cooling unit and serving not only as a conductor but also as an efficient "hold-over" whereby to replace the brine tanks as are now in common use in refrigerator "low sides". In addition to embedding the refrigerating coils in such stone cooling unit, the present invention embodies the embedding of alternately spaced brine circulating coils, such brine serving not only as a good "hold-over", and especially in case of stoppage, but also serving as a refrigerating medium for a separate refrigerating unit. This separate refrigerating unit is an important part of the present invention and is preferably of a type which only requires infrequent use of a refrigerating medium.

A further feature of the present invention has to do with the connecting of the alternately spaced brine circulating pipes of the stone cooling unit with the cooling unit of such separate refrigerating system, or means, whereby whenever desired the brine from the refrigerator cooler unit will be circulated by thermo-siphon action between the two units. The result of this is that one refrigerating apparatus and one motor need only be required, and such motor will be controlled by a single thermostat within the refrigerating chamber of the refrigerator, whereby when the brine within the pipes is used such thermostat will obviously cause actuation of the refrigerating apparatus to take care of the auxiliary heat absorption by such brine.

In the drawings:

Fig. 1 is a perspective view, partly cut away, showing a refrigerator provided with auxiliary brine circulating coils, and an ice cream freezer connected up with such brine circulating coils as to cause circulation of the brine through the same by thermo-siphon action.

Fig. 2 is a diagrammatic detail view illustrating the preferred arrangement of the

alternately positioned expansion coils which are embedded in the cast cooling unit.

Fig. 3 is a fragmentary sectional view showing the manner of cast embedding the coils in the stone wall of the cooling unit, the illustration having particular reference to the cooling unit of the freezer.

This application is a continuation, in part, of my pending application Serial No. 86,719, filed Feb. 8, 1926.

The particular structure illustrated in the drawings embodying my invention, comprises a refrigerator cabinet 1 which may be of any suitable standard structure and provided with a suitable refrigerating apparatus (not shown) which may be either located in the refrigerator cabinet itself, or below the cabinet according to the standard practice.

The refrigerator cabinet is provided with a cooling unit, or "low side" 2 which is preferably formed of cast stone and is a cooling unit similar in construction to the one illustrated and described in my copending application No. 118,429, filed June 25, 1926. This cooling unit is preferably formed of cast stone with suitable sharp freezing chambers and with the refrigerating coils suitably embedded therein. The inlet for connecting the cooling unit to the condenser of the refrigerating apparatus may be designated 3, and the outlet for connecting the coils of the cooling unit to the compressor may be designated 4, although it will be understood that such inlet and outlet may be located at any desired place in accordance with the particular construction.

Fig. 2 illustrates the preferred arrangement of the refrigerating coils which are cast embedded in the unit 2, such refrigerating coils being shown in dotted lines and designated 5. Suitable coils 6, similar to the coils 5 are also embedded in the walls of this cast cooling unit 2, and are alternately spaced between the adjacent coils 5. The coils 6 are adapted to contain brine, or other suitable non-freezing solution, and are preferably adapted to extend out of the cooling unit, as shown in Fig. 1. The inlet for the brine coils 6 may be designated 7 and the outlet 8, and as shown in Fig. 1, such inlet and outlet project through the wall of the refrigerator cabinet, although it will be understood that in normal practice that such inlet and outlet coils will preferably be conducted through the bottom of the refrigerator.

The cooling unit 2 is preferably provided

with a suitable thermostat which may be designated 9 and which is adapted to be connected to the refrigerating apparatus to automatically control the same in order to maintain the cooling chamber of the refrigerator at an approximate constant temperature. In other words, when the temperature of the cooling chamber rises above a certain degree, the thermostat will be effective to cause actuation of the refrigerating apparatus whereupon more of the refrigerant will be admitted and expanded to absorb the heat units around the cooling unit.

This refrigerator and refrigerating apparatus therein is therefore adapted to be used as a permanent unit in a home, and as well known, such automatic refrigerators are rapidly replacing the old fashioned ice boxes of the past. These new refrigerating units are adapted for the manufacturing of artificial ice, but not to any large extent as will be necessary in the freezing of ice cream and the cooling of other units requiring a relatively large amount of ice. I have, therefore, provided the brine circulating coils in the cooling unit and so connected the same with an ice cream freezer or other similar article whereby use is made of the refrigerating unit and the refrigerating apparatus, whereby to afford an efficient cooling unit whenever required.

This freezing unit, or ice cream freezer, may be generally designated 10. This freezing unit is preferably formed either wholly, or partially, of cast stone, and in the drawing this cast stone container may be designated 11. Whether formed wholly or partially of cast stone, such cast stone forms the cooling unit of the freezing apparatus and the brine circulating coils 6, which extend from the cooling unit 2, are preferably embedded in this stone container, as shown in dotted lines at 12.

Fig. 3 illustrates the preferred manner of embedding such brine circulating coils in the cast stone walls of the ice cream freezer. The outlet of such coils is preferably at 13, and the inlet is preferably at the base of the unit, as at 14. The inlet and outlet 7 and 8 may be provided with suitable valves, as shown, which may be positioned adjacent the wall of the refrigerating cabinet, within the refrigerating cabinet itself, or any desired place, and when such valves are open, it will be obvious, due to the positioning of the inlet and outlet 13 and 14, and to the fact that the refrigerator is preferably higher than the freezing unit, that a thermo-siphoning of the brine will take place, the cool brine from the cooling unit 2 replacing the brine in the ice cream freezer and forcing the same back up into the top part of the cooling unit to be in turn cooled.

The obvious place for the ice cream freezer, or other unit, will be in the cellar beneath the

refrigerator, but it will be understood that such ice cream freezer, or other unit, may be located at any convenient place, as desired, the point being that such unit is separate from the refrigerator, and that the cooling medium therefore is obtained by opening the connecting valves and permitting the thermo-siphon action. A suitable pump 15 may be inserted in the brine circulating line to insure positive efficient circulation, and possibly obtain a lower normal temperature within the freezing unit than when the thermo-siphon action is relied upon. The cast stone cooling unit for the ice cream freezer may be formed as a container to receive the ice cream can, and a suitable motor may be mounted upon the freezer to make the device completely automatic.

In operation, the refrigerator being a permanent part of the household, the brine circulating valves may be opened whenever the ice cream freezer is in condition for operation, and the cooled brine within the coils embedded in the cooling unit 2 will, by the thermo-siphon action set up, displace the higher temperature brine within the walls of the freezer unit. As the freezer is operated and the brine absorbs the heat therefrom, it will be obvious that the cooling unit 2 will have to absorb more heat from the brine, and that the thermostat will almost immediately operate to start positive operation of the refrigerating apparatus and the motor. As the heat absorption and heat transfer will be maintained practically constantly during the freezing operation, it will be obvious that the thermostat will be effective to automatically continue the operation of the freezing apparatus until the freezing has been accomplished.

It will therefore be seen that I have provided a novel apparatus whereby the refrigerating apparatus contained in a commercial electrical refrigerator can be utilized to perform or supply the heat absorbing medium for effecting the freezing of ice cream, and the operation of other similar articles ordinarily requiring a large amount of ice. It will also be seen that I have made it possible to utilize a single motor and to effectively and accurately control the operation of such motor whereby to automatically take care of the auxiliary unit whenever operated.

Having thus described my invention, what I claim is:

1. A domestic refrigerating system comprising a refrigerating unit provided with a refrigerating apparatus for continuous normal operation, a separate refrigerating unit adapted for infrequent operation, both of said refrigerating units being provided with cooling units, a refrigerant circulating means comprising pipes formed in a closed path and passing through the wall of said domestic refrigerating unit for connecting said cooling units and positioned in heat absorbing relation with the cooling unit of said first refriger-

erating unit, and means for stopping the flow of refrigerant between said two units.

2. A refrigerating system comprising a plurality of separate refrigerating units, one 5 a domestic refrigerator provided with mechanical refrigerating means, adapted for continuous automatic operation, and another adapted for infrequent operation, means utilizing the heat absorbing medium in the first 10 named unit to effect heat transfer and cooling of the second unit including pipes passing through a wall of said first unit, and means automatically actuated by the transfer of heat units in said continuously operated unit to 15 take care of the transfer of heat units to said auxiliary unit whenever actuated.

3. A refrigerating system comprising a refrigerator having a cooling unit of the automatic expansion type, a completely separate 20 refrigerating unit comprising an ice cream freezer, or similar article, and refrigerant coils positioned in heat conducting relation with said separate freezing unit, and in heat conducting relation with the cooling unit of 25 the refrigerator whereby to effect cooling of said separate refrigerating unit by thermosiphon action.

4. A refrigerating system comprising two 30 separate refrigerating units one a mechanically operated domestic refrigerator and the other an ice cream freezer, each provided with a cooling unit, non-freezing solution circulating pipes for connecting the cooling

units of the two said refrigerating units, means for effecting circulation of the non- 35 freezing solution by thermo-siphon action, and valves for shutting off the circulation of said non-freezing solution.

5. In a refrigerating system, the combination of a refrigerator provided with a cast 40 cooling unit, an expansion coil embedded therein, an ice cream freezer, or similar article, provided with a cast container, and non-freezing solution circulating pipes positioned in heat conducting relation with said cast cool- 45 ing unit and the walls of said cast container unit whereby such non-freezing solution will be cooled by the cast cooling unit and circulated throughout the pipes by thermosiphon action. 50

6. In a refrigerating system, the combination of a refrigerator provided with a moulded stone cooling unit, expansion coils and non-freezing solution coils positioned in heat conducting relation with such unit, 55 and an ice cream freezer or similar refrigerating unit provided with moulded stone cooling walls, the said non-freezing solution pipes being also positioned in heat conducting relation with said moulded stone walls whereby 60 said non-freezing solution pipes will absorb heat from said freezer, and the refrigerant circulating pipes will absorb the heat from said non-freezing solution pipes.

In testimony whereof I affix my signature.
LLOYD G. COPEMAN.
